BY *W. F. Stevens*.

ATTORNEY

UNITED STATES PATENT OFFICE.

ALBERT H. STEBBINS, OF LOS ANGELES, CALIFORNIA.

TABLE CONCENTRATOR.

Application filed July 19, 1926. Serial No. 123,333.

This invention relates to table concentrators and more particularly to the construction of the concentrator deck and means for attaching the deck to its supporting carriage.

In the concentrator decks now extensively used for treating materials in a dry condition, the deck surface is supported at a transverse inclination to cause the tailings to flow laterally over the deck surface toward the lower or tailing discharge side of the deck, and the riffles or channels upon the deck surface slope upwardly toward the concentrate wall to direct the concentrates away from the lower side of the deck as they travel along the riffles.

The type of concentrator just referred to wherein the riffles extend diagonally over the deck surface toward the concentrate wall, works very well in treating coarse and medium size materials but does not work well in treating fine dust-like materials, because the very fine concentrates tend to pile up and flow laterally over the riffles with the tailings.

One feature of the present invention therefore relates to a novel construction whereby the movement imparted to the deck to advance the materials along the riffles or channels serves also to work the concentrates transversely of the channels away from the discharge side of the channels.

This is accomplished by providing the deck surface with riffles or channels that extend across the path of deck movement in a direction to cause the movement to work the concentrates away from the discharge side of the channels. This arrangement of the riffles however directs the materials traveling along the riffles toward the lower or tailing side of the deck rather than up the transversely inclined deck as heretofore. It is therefore desirable to change the construction of the deck or supporting means for the same so that the materials traveling along the riffles will move up-hill as they approach the concentrate discharge end of the deck.

Another feature of the present invention therefore resides in a deck the discharge end portion of which slopes upwardly with respect to the remaining portion of the deck so that the materials travel up-hill as they approach the discharge end of the deck,

Another feature of the invention resides in the construction whereby the deck is pivotally secured to its supporting carriage by hinges that are arranged diagonally of the carriage, the arrangement being such that movement of the deck about its hinge connection will vary its inclination both longitudinally and transversely.

Another feature of the invention resides in shearing blades mounted within the material guide channels and adapted to direct out of the channels some of the materials traveling therein.

Still another feature of the invention resides in a deck supporting frame that is pivotally mounted for rocking movement about a transversely extending axis to thereby vary the inclination of the deck in the direction of its length.

Other features of the invention and novel combination of parts, in addition to the above, will be hereinafter described, in connection with the accompanying drawings, which illustrate good practical forms of the invention.

In the drawings—

Fig. 1 is a plan view of a concentrator deck constructed in accordance with the present invention, and showing the means for securing the deck to its carriage.

Fig. 2 is a side elevation of the deck and carriage of Fig. 1 mounted upon the supporting frame.

Fig. 3 is a side view of the construction of Fig. 1 looking towards the upper or concentrate side of the deck;

Fig. 4 is a transverse sectional view through the construction of Fig. 2.

Fig. 5 is a transverse sectional view through a modified type of deck; and

Fig. 6 is a perspective view of a portion of the deck of Fig. 5, showing shearing blades associated with the deck.

The concentrator deck to be described is mounted upon the deck supporting carriage 10 supported for vibratory movement in the direction of its length by the supporting frame constructed of the uprights 11 to which the longitudinally extending side rails 12 are secured. The means shown for supporting the carriage 10 upon the frame for vibratory movement consists of the bearing blocks 13 that are supported by the frame, and each of which has a groove in its upper

face adapted to receive a ball or roller 14 the upper portion of which projects into the groove of a similarly shaped bearing block 15 that is fastened to the under face of the 5 carriage 10.

It is desirable to impart a progressive vibratory movement to the concentrator deck to advance the materials lengthwise of the same. Any well known or preferred type 10 of operating means may be employed to this end and one good practical construction consists of the similar operating cables 16 an intermediate portion of each of which is rigidly secured to the carriage 10 by the 15 clamping blocks 17. One end portion of each cable 16 extends from its clamping block about an idle grooved sheave 18 that is rotatably supported by a transversely extending shaft 19 which shaft is supported 20 by the main frame of the concentrator. The portion of the cable 16 just mentioned extends downwardly from the grooved sheave 18 to a coiled spring 20 one end of which rests against a transversely extending beam 25 21 of the supporting frame, while the opposite end of the spring 20 acts against a nut or the like 22 attached to the end of the cable 16. The arrangement is such that the coiled springs 20 will exert a continuous pull 30 upon the cables 16 to urge the carriage 10 and deck mounted thereupon in a right-hand direction.

The opposite end portion of each cable 16 extends from a clamping block 17 in a left-hand direction about the grooved idle sheave 23 which is supported by the transversely extending shaft 24 and this cable extends from the lower portion of the sheave 23 about a second grooved sheave 25 which is 35 mounted upon an eccentric 26. This eccentric is secured to and is rotated by the power operated shaft 27 that is journaled in bearing brackets 28 supported by the main frame. The end portion of the cable 16 40 which extends from the lower side of the sheave 25 is anchored to the main supporting frame by any suitable means such as the adjustable bolt 29 having the nuts 30. The arrangement is such that rotation of the 45 power shaft 27 will rotate the eccentrics 26 within the sheaves 25 to thereby move the sheaves 25 in an orbital path. This will serve to alternately slack off and tension the portion of the cable which engages each 50 sheave 25 with the result that the deck will be pulled positively in a left-hand direction, and the cables will then be slackened off to permit the deck to move in a right-hand direction under the action of the springs 20, 55 and by varying the strength of the springs 20 the progressive movement may be made as energetic as desired.

As stated, one of the features of the present invention resides in the construction 60 65 whereby the movement imparted to the deck

will serve not only to advance the materials lengthwise of the deck, but also to cause the concentrates to work transversely of the material guiding channels so that the concentrates will work away from the discharge 70 side of the channels. This feature of the invention may be embodied in a deck having riffles extending over this deck surface, as shown in Figs. 1, 2 and 3, or may be embodied in a deck having the guide channels 75 formed by giving the deck the stepped construction shown in Figs. 5 and 6. The travel of the concentrates transversely of the channels towards the upper or concentrate side of the deck is effected by arranging the riffles or channels so that they extend downwardly across the path of deck movement, as will be apparent from Fig. 1, wherein the direction of the progressive movement imparted to the deck is indicated by the broken 80 line a—a.

The concentrator deck is preferably given the general configuration best shown in Fig. 1, wherein it will be noted that the deck is relatively narrow at its material receiving 90 end having the feed hopper 31, and is also relatively narrow at the opposite or concentrate discharge end 32. Along the upper side of the deck is provided a wall 33 which extends from the feed hopper 31 to the concentrate wall 34 which is provided with the usual buffer blocks 35, and along the lower side of the deck is provided a wall 36 that extends in an inclined direction from the feed hopper 31 to the tailing discharge portion 100 of the deck indicated by 37. The walls 33 and 36, it will be understood, are sufficiently high to prevent the materials being treated from falling off the deck. While the configuration of the deck just described 105 is desirable, this particular construction is not essential so long as the riffles or material guide channels are arranged so that they extend downwardly across the path of deck movement, as above pointed out, to cause the concentrates under the influence of the deck movement to work away from the discharge side of the deck.

The deck construction shown in Figs. 1 to 4 inclusive is provided with the upstanding 115 riffles 38 which may be of substantially the same height throughout their entire length, or if desired may taper from one end of the deck towards the other, as found desirable. The ends of riffles located near the upper 120 side of the deck may terminate along the concentrate wall to cause the concentrates to pile up against this wall for retreatment as usual.

It is important to note that the riffles 38 125 instead of extending diagonally over the deck surface towards the upper wall thereof, as has been customary heretofore, extend diagonally across the deck surface towards the lower or tailing discharge side of the deck 130

37. It will therefore be seen that the materials traveling within the channels between the riffles, instead of moving diagonally of the deck towards the upper side thereof as heretofore, move downwardly across the deck towards the lower side thereof, but it is desirable to cause the materials traveling within the channels to travel up-hill as they advance along the deck surface, in order to slow down somewhat the progress of the materials along the deck surface and gives the concentrates an opportunity to work downwardly under the tailings to force the latter out of the channels.

15 In order to impart this up-hill movement to the materials the deck of the present invention has the portion of the same adjacent to the concentrate discharge end bent upwardly, as will be apparent from Figs. 2 and 3, 20 wherein the upwardly bent end portion of the deck is clearly shown.

The desirable construction just mentioned, whereby the materials traveling along the deck surface are caused to move up-hill as they approach the discharge end of the deck, may be further secured by fastening the deck to the deck supporting carriage 10 by a row of hinges 39 arranged so that the axis of the hinges extends diagonally of the carriage 10, as clearly shown in Fig. 1. As a result of this arrangement rocking movement of the deck about the hinges will serve to vary the inclination of the deck both longitudinally and transversely, instead of transversely alone, as is the case when the hinges are arranged along the lower side of the carriage 10. This will be better understood upon reference to Fig. 3 wherein it will be seen that the portion of the deck lying near the concentrate discharge end 32 is elevated a substantial distance from the supporting carriage 10, and it will be apparent that this elevation of the deck is due not only to the fact that the end portion of the deck is bent upwardly, as above pointed out, but largely to the arrangement of the diagonally disposed hinges just mentioned. The upper side of the deck and the portion thereof near the discharge end 32 may be supported by a number of adjustable bolts 40 the upper ends of which are provided with ball heads 41 mounted in sockets 42 secured to the under face of floor 43 of the deck surface, and the lower ends of the bolts 40 are adjustably secured to the carriage 10 by the nuts 44.

As a result of the construction so far described it will be seen that the materials traveling along the channels formed between the riffles 38 will tend to work away from the lower wall of a channel under the influence of the progressive deck movement. This tendency of the materials to work laterally across the channels towards the upper side of the deck will be more effective upon the concentrates than upon the tailings and

as a result the concentrates in working away from the lower side of each channel will crowd the tailings upwardly and towards the lower side of the channels so that in this manner the tendency of the concentrates to escape over the lower side of the channel with the tailings is materially reduced. The deck construction of the present invention whereby the concentrates are caused to work away from the lower or tailing discharge side of the channels is particularly desirable in treating fine, dust-like materials, since these fine values tend to flow over the sides of the riffles with the tailings unless they are forced away from this side of the riffles in the manner above pointed out.

Instead of providing the deck surface 45 with the channel forming riffles 38, the material receiving channels may be formed by giving the deck the stepped construction shown in Fig. 5 wherein it will be seen that each channel 46 has a floor portion 47 and an upstanding portion 48 and it should be noted that each floor portion 47 slopes transversely in a downward direction away from the lower side of the deck so that the slope of the floor portion 47 will help to direct the materials away from the discharge side of each channel 46. If the channels 46 are given the same size throughout their length it may be desirable to provide means for forcing the tailings out of these channels as the materials approach the concentrate wall or discharge end of the deck, and this may be accomplished by the construction shown in Fig. 6 wherein it will be seen that the channels 46 are provided with the shearing blades 49. These blades are preferably pivotally secured within the channels by bolts or other securing means 50 so that the blades may be adjusted to different angles transversely of the channels to vary the amount of materials directed out of the channels by the shearing blades. These shearing blades may be arranged in the channels over the deck surface as found desirable.

In some constructions it may be desirable to provide means whereby the longitudinal inclination of the deck may be varied, and to this end in the construction shown the deck supporting frame is mounted so that the entire table concentrator, including its supporting frame, may be shifted about a transversely extending shaft or fulcrum 51, the intermediate portion of which shaft is mounted in a supporting bracket 52, which may be secured to the floor 53 formed of concrete or other suitable material, and the end portions of the shaft 51 are journaled in bearing brackets 54 secured to the side rails 12 of the main frame. The arrangement is such that the deck supporting frame may be rocked about the shaft 51 to different inclinations in the direction of its length, and after it has been tilted to a desired posi-

tion it may be secured in this position by placing blocks 55 under the frame and by clamping the frame to the floor by the bolts 56.

5. What is claimed is:—

1. A table concentrator, comprising in combination, a deck supporting frame, a deck mounted upon the frame at a transverse inclination and having a concentrate wall extending along the upper side of the deck, and against which the concentrates are directed for retreatment, means for imparting vibratory movement to the deck in the direction of its length, a series of material receiving channels extending over the deck surface to terminate along the concentrate wall and arranged so that they extend longitudinally downwardly across the path of deck movement toward the lower side of the deck to cause the concentrates to work transversely of each channel in the direction of the concentrate wall and away from the tailing discharge side of the channels, and means for supporting the deck so that the materials traveling along the channels are required to travel uphill as they approach the discharge end of the deck to thereby promote the tendency of the concentrates to crowd the tailings out of the channels.
2. A table concentrator, comprising in combination a deck supporting frame, a deck mounted upon the frame at a transverse inclination and having a concentrate wall extending along the upper side of the deck and against which the concentrates are directed for retreatment, means for imparting vibratory movement to the deck in the direction of its length, a series of material receiving channels extending over the deck surface to terminate along the concentrate wall and arranged so that they extend longitudinally downwardly across the path of deck movement toward the lower side of the deck to cause the concentrates to work transversely of the channels in the direction of the concentrate wall and away from the discharge side of the channels, and said deck having its discharge end portion inclined upwardly to cause the materials traveling along the channels to travel up-hill as they approach the discharge end of the deck to thereby promote the tendency of the concentrates to crowd the tailings out of the channels.
3. A table concentrator comprising in combination, a deck supporting frame, a deck carriage supported by the frame for vibratory movement, a deck mounted upon the carriage and having a concentrate wall extending along the upper side of the deck but diagonally of the supporting frame and also of the path of deck movement, a deck surface provided with guide channels for guiding the materials over the deck surface toward the concentrate wall, and means for adjustably connecting the deck to the car-

riage, comprising a row of hinges disposed diagonally of the deck supporting frame and in substantially parallel relation to the concentrate wall but at the opposite side of the deck so that the entire deck may be rocked about the row of hinges to vary the inclination of the deck both longitudinally and transversely.

4. A table concentrator comprising in combination, a deck supporting frame, a deck carriage supported by the frame for vibratory movement in the direction of its length, a deck mounted upon the carriage and having a concentrate wall extending along the upper side of the deck diagonally of the supporting frame and also of the path of deck movement, a deck surface provided with guide channels for guiding the materials over the deck surface toward the concentrate wall and which are arranged to extend across the path of deck movement in a direction to cause the concentrates to work transversely of each channel toward the concentrate wall, and means for adjustably connecting the deck to the carriage, comprising a row of hinges disposed approximately parallel to the concentrate wall but at the opposite side of the deck and diagonally of the supporting frame so that the entire deck may be rocked about the row of hinges to vary the inclination of the deck both longitudinally and transversely.

5. A concentrator deck, comprising in combination, a deck surface provided with a series of material guide channels, means for actuating the deck to advance the materials along the channels, shearing blades arranged to extend part way across the channels to deflect therefrom some of the materials traveling within the channels, and means for supporting the shearing blades for adjustment to different positions within the channels.

6. A concentrator deck, comprising in combination, a deck surface having a stepped construction formed to provide a series of material guide channels each having an up-standing wall portion and a floor portion that slopes downwardly toward the wall portion, means for actuating the deck to advance the materials along the channels, shearing blades arranged to extend part way across the channels to deflect therefrom some of the materials traveling within the channels, and means for supporting the shearing blades for adjustment to different positions within the channels.

7. A concentrator deck, comprising in combination, a deck surface having a stepped construction formed to provide a series of material guide channels each having an up-standing wall portion and a floor portion that slopes downwardly toward the wall portion, means for actuating the deck to advance the materials along the channels,

shearing blades mounted in said channels and adjustable toward and from said upstanding wall portion to deflect from the channels some of the materials traveling within the channels, and means for supporting the shearing blades in different positions of adjustment.

8. A concentrator deck, comprising in combination, a deck surface having a stepped construction formed to provide a series of material guide channels each having an upstanding wall portion and a floor portion that slopes downwardly toward the wall portion, means for actuating the deck to advance the materials along the channels, and a shearing blade mounted in a channel in spaced relation to a wall portion thereof to provide a restricted passage between the shearing blade and said wall through which the concentrates may pass while the tailings

are deflected out of the channel by the shearing blade.

9. A concentrator deck, comprising in combination, a deck surface that is supported at a transverse inclination and which is provided with a series of material receiving channels, means for actuating the deck to advance the materials along the channels and to promote flow of the tailings down the inclined deck surface from one channel to the next, and a shearing blade mounted in a channel to deflect the tailings therefrom and arranged to extend from the discharge side of the channel toward the opposite wall thereof to form a restricted concentrate passage between its end and said wall.

In testimony whereof, I have signed my name to this specification.

ALBERT H. STEBBINS.
